CURTAIN ROD LEADER

Filed Sept. 7, 1920

Fig. 1.

Fig. 2.

Inventor:

*Nellie Folsom Mansure,
By my birth name, Christine Miles,
H. H. Miles.*

UNITED STATES PATENT OFFICE.

NELLIE FORSMAN MANSURE, OF CHICAGO, ILLINOIS.

CURTAIN-ROD LEADER.

Application filed September 7, 1920. Serial No. 408,486.

To all whom it may concern:

Be it known that I, NELLIE FORSMAN MANSURE, a citizen of the United States, residing at Chicago, in the county of Cook and State of Illinois, have invented a new and useful Improvement in Curtain-Rod Leaders, of which the following is a specification.

This invention relates particularly to a device which may be employed as a curtain-rod tip or thimble, in connection with curtain rods of different sizes, to facilitate the introduction of the curtain-rod into or through the loop of a curtain.

15 The primary object is to provide a simple and cheap device which is well adapted for use in connection with curtain-rods of different sizes, for the purpose indicated.

The invention is illustrated in its preferred embodiment in the accompanying drawing in which—

Fig. 1 represents the improved curtain-rod leader, partly in section and partly in elevation, applied to a curtain-rod (shown brokenly), the dotted lines indicating curtain-rods of different diameters and illustrating how the improved device is adapted for interchangeable use; and Fig. 2 represents, by a broken elevational view, a curtain, the view illustrating the manner in which the curtain-rod is entered through the loop of the curtain.

In the illustration given, A represents a curtain-rod; B, an improved curtain-rod leader; and C, a curtain provided at its upper end with a loop C'.

The device B comprises an elongated shell, which preferably is formed of sheet metal, but which may be cast in the form shown, if desired. The shell, however, may be drawn from a disk of metal. In the form shown, the shell comprises a tip-end section 1, of small diameter, an intermediate section 2 of larger diameter, and a rear end section 3 of still larger diameter. The section 1 preferably is completely closed at its advance end and presents a tapered portion 1^a at its front end. The intermediate section 2 has a tapered portion 2^a at its front

Similarly, the rear section 3 presents a tapered portion 3^a at its front end, which joins the rear end of the section 2. The sections are of substantially cylindrical form, so as to afford a firm bearing or secure socket for 55 the end of the curtain-rod, the advance end of each section being curved or tapered to facilitate the passage of the leader through the loop of the curtain.

In the form illustrated, the device B is 60 adapted for use in connection with curtain rods of three different sizes, as for instance, a quarter inch rod, a three-eighths inch rod, and a half inch rod. The rod A of intermediate size is shown engaging the intermediate socket 2 of the device B. Rods A' and A² of smaller and larger size, respectively, are shown in dotted lines as engaging the socket portions 1 and 3 of the device.

The improved device is of simple construction, may be manufactured cheaply, is adapted to be applied with sufficient security to rods of varying sizes, and is well adapted to its purpose. Should the device, for any reason, become disconnected from the rod 70 while insertion through the loop of the curtain is being made, it is possible to again enter the rod in the thimble, because of the fact that the thimble is of rigid form and open at one end for free insertion of the 75 rod.

What I regard as new and desire to secure by Letters Patent is—

1. An article of manufacture, consisting of a thimble comprising a plurality of cylindrical socket sections of successively reduced size, each cylindrical section having substantially parallel walls and being joined to the adjacent section by tapering walls, the small end section having a closed tip. 80

2. An article of manufacture consisting of an integral shell comprising a small cylindrical tip-end socket-section closed at its advance end, an intermediate cylindrical socket-section of larger diameter, and a rear end cylindrical socket-section of still larger diameter, each of said sections tapering at its advance end and having the walls of its main portion substantially parallel. 95
